UNITED STATES PATENT OFFICE.

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS.

ELECTRIC STOVE.

Application filed April 10, 1924. Serial No. 705,442.

This invention relates to electric stoves and ranges and has more particular reference to the construction and location of the current-inlet connections, that is, those carrying the electric current to the heaters or burners and including certain accessories such as the fuses and the switches which control the supply of current to the heaters.

Heretofore it has been customary to mount the control switches at the front of a stove below the cooking top thereof, or on the front of the oven structure or cabinet. In these locations the switches are generally quite low and within the reach of children, which is objectionable. Moreover, they are close to the heaters or burners and subject to heat radiated or conducted from the heaters, which has a tendency to damage the switches and wiring.

The primary purpose of the present invention is to obviate the objections noted and to improve the construction and operation of electric stoves and ranges by locating the current-inlet connections on a back wall or panel above the cooking top, so that the switches and fuses are beyond the reach of children and out of the heat zone. This also simplifies the construction, locates practically all wiring at the back of the stove, out of the way, and makes for neater and more symmetrical design, especially at the front of the cooking top.

Another purpose is to provide an improved construction of the character described which may be produced at a comparatively low cost and will serve in a practical and effectual manner the purposes intended.

Other objects and attendant advantages will be appreciated by those skilled in this art as the invention becomes better understood by reference to the following description when considered in connection with the accompanying drawings, in which—

Figure 1, is a perspective view of an electric range embodying my invention;

Fig. 2, is an enlarged fragmentary view of the control panel;

Fig. 3, is a vertical sectional view taken substantially on the line 3—3 of Fig. 4; and

Fig. 4, is a horizontal sectional view taken substantially on the line 4—4 of Fig. 3.

My invention may be embodied in any electric stove or range but is preferably adapted for those of the so-called cabinet type shown in the drawings. This range has

a cooking top designated generally by 5 comprising in this instance two top grate sections 6 and 7 removably mounted on the top frame 8 and each carrying front and rear heaters or burners 9 and 11 respectively, each made up of a series of individual heating units 12. The particular constructions of the heaters or burners is not important to the present invention, it merely being essential that the cooking top shall comprise one or more electric heaters.

In the present instance the heating units of each burner are connected at their ends to bus bars 13 (Fig. 3) which make connection at one end with suitable terminals or electrical contact members designated generally by 14 carried by insulation blocks 15 passing through and mounted on the rear wall 16 of the stove frame. In each of the ovens 17 and 18 is located a number of electric heaters or burners (not shown) which may be detachably connected to electric contact members at the back of each oven similar to the members 14.

My invention contemplates assembling and mounting the current-inlet connections entirely enclosed in what amounts to a junction box upon or in connection with the rear wall or frame structure of the stove, the connector blocks 15 being part of said connections. On the rear wall or panel 19 above the cooking top I mount a switch base or block 21 of insulation material preferably at the back of said panel through the agency of suitable means such as a bracket 22. In the present instance there are a series of individual switch bases or blocks secured by bolts 23 to the bracket 22. Each switch base has one or more sockets for the reception of an enclosed plug fuse 24 and carries therebelow a rotary multi-pole snap switch designated generally by 25 having an operating member reaching through the panel 19 and equipped in front thereof with a suitable handle 26 by means of which the switch may be manually operated.

Inasmuch as the electric circuit per se might be conventional or otherwise I have not deemed it necessary to illustrate a wiring diagram showing the connections between the fuses, switches and burner connectors. It is believed that it will suffice to say that any conventional wiring diagram might be employed and that the current-inlet connections are fully illustrated so far as the pres-

ent invention is concerned by the showing of the fuses, switches, the wiring 27 connecting the fuses and switches and the wiring or leads 28 connecting the switches and binding posts 29 on the rear of the connector blocks 15, which posts are part of the terminals 14. It will be manifest to those skilled in this art that the lead wires to all of the burners may be arranged at the back of the 10 stove in substantially the manner disclosed herein. A suitable casing or housing 31 encloses the current-inlet connections at the back of the stove.

The fuses 24 are accessible from the front 15 of the stove through an opening 32 reaching horizontally across the top of the panel 19, said opening being normally closed by a door 33 pivotally mounted at its upper end 34 and adapted to be swung upwardly to an open position and to rest on the top of the casing 31 as indicated in dotted lines in Fig. 3.

The usual shelf 35 may be supported on the back panel preferably below the switches and serves its usual purpose without appreciable interference by the switch handles. 25

It is believed that from the foregoing many of the advantages of my invention will be apparent. The switches are on a control panel located in a high position so as to be more 30 nearly on a level with the eyes of the user and more easily readable with respect to the indicia "High", "Medium", "Low" and "Off", than when located below the cooking top. This high position also prevents tampering 35 by children. The switch handles are set back so as not to project beyond the front wall of the stove and be subject to accidental turning by contact of moving bodies. The arrangement of the current-inlet connections are out 40 of the heating zone so that neither the wiring nor the switch mechanisms are impaired by heat from the burners. This arrangement centralizes the wiring and makes for

more direct connection. By removing the switch mechanism, fuses and wiring from the front of the stove the front burners may be brought farther forward and still allow plenty of room on the cooking top in front of the burners for utensils. The present current-inlet connections are out of the way so as not to be injured by the accidental spilling or boiling over of water or other liquids. The arrangement is further desirable because it promotes simplicity in construction and an unobstructed front below the cooking top 55 which improves the appearance.

It is believed that the foregoing conveys a clear understanding of the objects prefaced above and while I have illustrated but a single working embodiment it should be understood that many changes might be made in the construction and arrangement without departing from the spirit and scope of the invention as expressed in the appended claim, in which

I claim:

In an electric stove having a cooking top and an upright panel at the back thereof, electric heating units for the cooking top, and a junction box at the back of said panel extending substantially from the cooking top to the top of the panel for enclosing current-inlet connections for the electric units, said connections comprising terminal connections at the back of said panel for said heating units, an upright block structure of insulation material within the junction box near the top thereof, vertically spaced rows of switches and plug fuse sockets on the front of said block structure, switch handles in front of the panel for operating the switches, and wiring within the junction box connecting the fuse sockets, switches and terminal connections.

STANLEY H. HOBSON.
